UNITED STATES PATENT OFFICE.

MARION B. HOPKINS, OF ELIZABETH, NEW JERSEY, ASSIGNOR TO STANDARD DEVELOPMENT COMPANY, A CORPORATION OF DELAWARE.

NITRATION PROCESS.

No Drawing.

Application filed March 18, 1922. Serial No. 544,949.

The present invention relates to the nitration of aliphatic and cyclo-aliphatic or non-benzenoid compounds, and will be fully understood from the following description 5 thereof.

In accordance with the present invention, the hydrocarbon to be nitrated is subjected to the action of nitric acid, the total amount of which is in excess of that theoretically necessary for the production of the mono-nitro derivative, in the presence of aluminum nitrate, which may be employed either in the form of the crystals or the anhydrous compound. The nitric acid is preferably added 10 to the hydrocarbon in the presence of the aluminum nitrate in two or more batches, although the entire quantity of nitric acid may be added at the beginning of the operation, if desired. The nitric acid and the 15 hydrocarbon are heated together in the presence of the aluminum nitrate to 115° C. or higher, the temperature varying with the boiling point of the hydrocarbon for example, by the use of an oil bath maintained 20 at a temperature 10 to 20° higher than the desired temperature. The vapors passing off from the heated mixture are condensed and the distillate is returned, after separation of the water, intermittently or continuously, as desired, to the reacting mixture. 25 The heating of the mixture is continued under these conditions, for a period of 6 to 9 hours or until the nitric acid becomes substantially inactive. At the end of this period 30 the oily products in the reaction chamber are separated from the viscous aluminum nitrate layer and the mono and di-nitro compounds present therein separated by distillation with steam. The mixture of nitro- 35 compounds is found to contain some unchanged hydrocarbon. The proportion of mono-nitro compounds varies, and in the case of octane, for example, is from 40 to 40% of the hydrocarbon consumed in the 40 action, and the proportion of crude di-nitro compounds from 50 to 60% of the hydrocarbons. The following specific example 45 illustrates a procedure which may be employed in carrying out the present invention: 50

About 1400 parts by weight of an octane fraction of petroleum, boiling between 125 and 130° C. is admixed with 1000 parts of 55 94% aluminum nitrate and 600 parts of 68% nitric acid. The mixture is heated in an oil

bath maintained at a temperature between 130° C. and 140° C. The mixture of aluminum nitrate and nitric acid form a viscous layer upon which the hydrocarbon oil floats. During the heating a mixture of water, hydrocarbon and nitrogen oxide distill off from the mixture and this distillate is condensed, the hydrocarbon separated from the aqueous liquid, and returned to the reaction mass at intervals. After nine hours heating, the 60 nitric acid becoming substantially inactive, the reaction mass is permitted to cool and 600 parts additional of 68% nitric acid is stirred into the aluminum nitrate layer. The heating is then continued under the same 65 conditions for about six hours. The mixture is then allowed to cool. The nitro-compounds admixed with unchanged hydrocarbon separating from the viscous aluminum nitrate and nitric acid mixture as an oily 70 layer. This oily layer is of itself useful as a solvent, for example, for resinous materials, cellulose derivatives, etc. The oily layer of nitro-compounds is removed and 75 distilled with steam. The unchanged hydrocarbon and the mono-nitro compounds are volatile with steam, and, from 1400 parts of the oily mixture produced, 950 parts of mixed hydrocarbon and mono-nitro compounds were obtained as a steam distillate. 80 Of this 580 parts is unchanged hydrocarbon and 370 parts crude mono-nitro hydrocarbon. The undistilled residue is crude di-nitro compound. The mono-nitro compound is distilled under reduced pressure to effect 85 its purification, and upon examination, is found to be a fairly pure nitro-octane. The di-nitro compound is likewise found to be substantially entirely di-nitro octane.

The process is particularly applicable to 90 the aliphatic and cyclo-aliphatic hydrocarbons having a boiling point of 115° C. or higher. The nitration of nonane, decane, mixtures of octane and nonane and of nonane and decane, and of gasoline, as well 95 as of cyclo-hexane and other cyclo-aliphatic compounds has been successfully accomplished by means of the present process. In such reactions the average yield of crude mono-nitro derivatives has been from 40 to 100 59% of the hydrocarbon consumed, and the yield of crude di-nitro compound from 50 to 60% of the hydrocarbon consumed.

I claim:

1. The process of nitrating non-benzenoid 110

hydrocarbons which consists in heating the hydrocarbon to a temperature of at least 115° C. and not substantially above its boiling point in the presence of nitric acid and 5 aluminum nitrate.

2. The process of nitrating non-benzenoid hydrocarbons which consists in heating the hydrocarbon to a temperature of at least 115° C. and not substantially above its boiling point in the presence of nitric acid and 10 aluminum nitrate, separating unchanged hydrocarbons from the vapors evolved, and returning the separated hydrocarbon to the reacting mixture.

15 3. The process of nitrating aliphatic hydrocarbons which consists in heating the hydrocarbon to a temperature of at least 115° C. and not substantially above its boiling point in the presence of nitric acid and 20 aluminum nitrate, separating the residual aluminum nitrate and nitric acid from the nitro-compounds produced and subjecting said nitro-compounds to distillation below their boiling point to separate the mono-nitro derivatives from the higher nitrated derivatives.

4. The process of nitrating aliphatic hydrocarbons of the gasoline range of boiling point which consists in heating such hydrocarbons to a temperature of at least 115° C. and not substantially above its boiling point with at least a molecular proportion of nitric acid in the presence of aluminum nitrate.

30 5. The process of nitrating non-benzenoid hydrocarbons which consists in heating the

hydrocarbon to a temperature of at least 115° C. and not substantially above its boiling point with less than a molecular proportion of nitric acid in the presence of aluminum nitrate, continuing the reaction until 40 the nitric acid becomes substantially inactive, supplying in the mixture additional nitric acid sufficient to bring the total quantity of nitric acid to at least a molecular proportion and continuing the heating of the reaction mixture.

45 6. The process of nitrating aliphatic hydrocarbons, having a boiling point within the gasoline range of boiling points, which consists in heating the hydrocarbon to a 50 temperature of at least 115° C. and not substantially above its boiling point with less than a molecular proportion of nitric acid in the presence of aluminum nitrate, continuing the reaction until the nitric acid becomes substantially inactive, supplying in the mixture additional nitric acid sufficient to bring the total quantity of nitric acid to at least a molecular proportion and continuing the heating of the reaction mixture.

55 7. The process of nitrating octane which consists in heating octane to a temperature of at least 115° C. with at least a molecular proportion of nitric acid in the presence of aluminum nitrate.

60 8. As an article of manufacture, a liquid containing octane, mono-nitro-octane and di-nitro-octane.

MARION B. HOPKINS.
